UNITED STATES PATENT OFFICE.

HARRY E. TOWNSEND, OF BROOKLYN, NEW YORK, ASSIGNOR TO ANCHOR CAP & CLOSURE CORPORATION, OF BROOKLYN, NEW YORK, A CORPORATION OF NEW YORK.

FRICITION SIDE SEAL.

1,365,295.

Specification of Letters Patent. Patented Jan. 11, 1921.

Application filed May 15, 1917. Serial No. 168,774.

To all whom it may concern:

Be it known that I, HARRY E. TOWNSEND, a citizen of the United States, and a resident of the city of Brooklyn, in the county of 5 Kings, State of New York, have invented certain new and useful Improvements in Friction Side Seals, of which the following is a specification.

This invention relates broadly to closures 10 and more particularly to a metal clip closure as applied to glass receptacles.

The principal object of the present invention is to provide a closure cap for glass receptacles and the like wherein a friction seal 15 is maintained between the closure and the side wall of the receptacle by forces tending to restore the skirt of the closure to normal condition prior to the displacement when the seal is forced over the receptacle, and 20 wherein the restoring forces have an action somewhat resembling a toggle action.

A further object of the present invention is to provide a closure for glass receptacles and the like wherein the closure cap is maintained 25 in position on the receptacle by friction contact at a sealing zone which is substantially the same for varying sized receptacles capable of being sealed by a particular sized closure.

30 A further object of the invention is to provide a closure designed for use on rigid receptacles, which is susceptible of removal from and effective re-use upon suitable vessels, the construction being such that the cap is not distorted or mutilated in removal 35 and the resilient properties of the material are retained so as to be effective in exerting a gripping action upon the vessel.

A still further object of the present invention 40 is to provide a closure comprising a friction seal for glass receptacles and the like and wherein the cross-section of the skirt of the cap is substantially two sides of a triangle with the sealing zone at the apex thereof.

Other and further objects of the present invention will in part be obvious and will in part be pointed out hereinafter in the specification following by reference to the 45 accompanying drawings wherein like parts are designated by like characters throughout the several figures thereof.

Figure 1 is a detail view illustrating a por-

tion of the skirt of the cap in section prior to being seated on the receptacle. 55

Fig. 2 is a detail view illustrating the cap seated on a relatively large sized receptacle and wherein the angle adjacent the sealing zone has been increased to relatively 60 large degree.

Fig. 3 illustrates a completed package sealed in accordance with the present invention.

Fig. 4 is a detail view showing the closure 65 on an "undersized" glass.

There is comparatively little prior art in friction seal closures for glass receptacles, the principal art being the closure disclosed in my prior application, filed May 16, 1916, Serial No. 97,871. The closure therein 70 disclosed includes a cover cap having a skirt provided with a curved groove which is adapted to contact with the side wall of a receptacle and to form a sealing zone therewith. This type of seal has been very successful 75 and the present invention comprises an improvement in the art along the lines of this particular closure. In the present case the skirt of the closure is provided on its exterior with a groove which provides a bead on 80 the interior of the skirt and which bead comprises substantially straight conical portions oppositely inclined to provide at their junction an apex or ring of restricted area that is adapted to comprise the sealing zone. 85

In this type of cap the seal is effected by forcing the skirt over the substantially incompressible side wall of the glass receptacle or the like and it will be noted that the exterior angle between the conical members 90 is increased thereby leaving the material under compressive force at the sealing zone point, which compressive force comprises the summation of forces acting through the conical members somewhat after the fashion 95 of a toggle action. The portions of the material lying in the original or outer annular zone of the skirt 2 form continuous circum-

ferential restricting members which act under tension to hold the in-pressed portion of 100 the skirt under compression against the side of the vessel when the cap is in place. Variations in the circumference of the sealing zone are accommodated by the relative movement of these circumferential restricting members in the direction of the skirt's 105

depth. This construction permits the forming of a very tight friction seal on a relatively restricted zone of narrow width so that the gripping action between the skirt of 5 the cap and the side wall of the receptacle is very effective. A cap of this construction will accommodate a considerably greater variation of sizes of vessels than those heretofore employed and, because of the fact that 10 the sealing zone, or the zone of contact between the crown 7 of the internal bead and the side of the container, is not materially widened when the cap is used on an oversized vessel, the advantage of the narrow 15 sealing zone is maintained in all applications of this closure.

Referring now to the drawings, the preferred embodiment of the present invention comprises a closure cap provided with a 20 cover portion 1 from which depends a skirt 2 that is provided with an inwardly inclined conical portion 4 which meets an outwardly inclined conical portion 5, as at 6. These conical portions 4 and 5 form a groove on the exterior of the skirt of the cap and form a bead on the interior of the skirt of the cap with the smallest internal diameter of the bead, namely the ridge 7, adapted to contact with the side wall 8 of the receptacle 9. To 25 seal a receptacle with this cap it is merely necessary to force the cap over the side wall 8 of the receptacle 9 and a seal is effected by the reaction in the resilient material of the bead which tends to resist the outward 30 displacement of the crown of the bead by the pressure of the vessel. This concentrates the compressive forces set up in the material of the cap upon the narrow crest of the bead which has bearing on the peripheral surface 35 of the vessel, and this concentration of the constricting or compressive forces upon this narrow sealing zone is effective appreciably to compress the metal at the crest of the bead into irregularities on the sealing surface 40 of the vessel. This provides a seal which is practically water-tight on vessels of ordinary commercial finish. As previously stated Fig. 2 indicates a seal being formed on an "over size" glass whereas Fig. 45 4 shows the seal being formed on an "under-size" receptacle.

Realizing that my invention may be capable of embodiment in structures other than those specifically disclosed I desire that the 55 disclosure herewith be understood as illustrative and not in the limiting sense.

By virtue of this construction of the portions of the cap which are active in constituting the side seal, the cap is susceptible to 60 removal from the vessel without distortion or mutilation and may be used again upon the vessel, or upon similar vessels, to form an effective side seal, as in the first use. The construction conserves the resiliency of the 65 material which is effective to exercise the

gripping action upon the vessel, so that, after the original use and removal of the cap, the same effective action of the parts is maintained.

Having thus described my invention what 70 I claim is:—

1. As an article of manufacture, a closure cap for application to rigid walled containers, comprising a cover portion adapted to form a closure for the mouth of a suitable 75 vessel and an annular skirt portion depending from said cover portion to encompass the side wall of the vessel; said skirt portion being formed of resilient material and being provided with an inwardly struck 80 bead extending in the circumferential direction of the skirt, which bead is pre-formed in substantially angular cross-sectional form before application of the cap to the vessel and with the crest of the bead providing a 85 narrow contact member for engagement against the wall of the vessel, said contact member being disposed on a circumference smaller than that of the vessel wall portion on which it is designed to seat and the sides 90 of the bead diverging outwardly therefrom, whereby the material in the bead may be placed under tension in its application to a rigid vessel so as to exert a resilient toggle-like action effective to maintain the 95 crown of the bead in close contact with the peripheral surface of the vessel wall, and to permit removal of the cap intact.

2. As an article of manufacture, a closure cap for application to tumblers and the like, 100 comprising a cover portion constructed to form a closure for the mouth of a suitable vessel and an annular skirt portion depending from the cover portion in position to encompass the side wall of the vessel; the 105 said skirt portion being formed of resilient material and being pre-formed, before application to a vessel, with an inwardly struck rib of angular cross-sectional form extending in the circumferential direction 110 of the skirt, the crest of the said angular rib providing a narrow contact member inside of the cap for frictional retaining engagement against the peripheral face of the vessel and being formed on a shorter radius 115 than the peripheral surface of the vessel upon which it is designed to seat; and portions of the skirt not included in said rib forming constraining members effective 120 upon the material in the rib to resist expansive movement thereof under pressure applied to the crest of the rib, whereby the cap is adapted for effective application to and removal from a suitable container repeatedly.

3. As an article of manufacture, a closure cap for application to tumblers and the like, comprising a cover portion adapted to form a closure for the mouth of a suitable vessel and an annular skirt portion of substantial 125

depth depending from the cover portion and adapted to encompass the side wall of the vessel; said skirt portion being pre-formed with an inwardly protruding portion 5 extending in the circumferential dimension of the skirt and having angularly diverging sides and an inwardly presented crest providing a narrow contact portion disposed on a smaller circumference than the vessel wall portion upon which it is 10 designed to seat and adapted to engage the peripheral surface of the vessel under tension, the sides diverging outwardly to the perimeter of the skirt adjacent its upper and lower limits, the material in said inwardly protruding portion being of resilient quality and the side portions thereof being susceptible of convergent and divergent movement whereby to permit outward movement 15 of the contact portion when the cap is forced onto the vessel.

4. As an article of manufacture, a closure cap for application to tumblers and the like comprising a cover portion adapted to 20 form a closure for the mouth of a suitable vessel and an annular skirt portion depending from the cover portion and adapted to encompass the side wall of the vessel; said skirt portion being of resilient material and pre-formed with an inwardly struck bead 25 having its upper side inclined inwardly and its lower side inclined outwardly and with the crest of the bead providing a narrow contact portion adapted to engage the peripheral surface of the vessel under tension of the resilient material in the skirt, the crest being formed on a circumference smaller than that of the vessel wall portion 30 on which it is designed to seat and the sides of the bead diverging outwardly to the perimeter of the skirt toward its upper and lower limits and being susceptible of convergent and divergent movement whereby to permit outward movement of the contact 35 portion of the bead without increase in its width, the portions of the skirt not included in said bead forming constraining members effective to resist outward movement of the crest of the bead.

5. As an article of manufacture, a closure cap for application to tumblers and the like, 40

comprising a cover portion adapted to form a closure for the mouth of a suitable vessel and an annular skirt portion depending from the cover portion and adapted to encompass the side wall of the vessel; said skirt portion being of considerable depth and pre-formed with an annular inwardly struck bead of angular cross-sectional form 45 with the crest of the bead providing a narrow contact portion on a shorter radius than the rest of the skirt than the wall portion of the vessel upon which it is designed to seat and adapted to engage the peripheral surface of the vessel under resilient tension of the material in the skirt, and the sides of the bead diverging outwardly to the perimeter of the skirt, and material in said bead being of resilient quality and the side portions thereof being susceptible of convergent and divergent movement whereby to permit outward movement of the contact portion of the bead without increase in its width. 50

6. As an article of manufacture, a closure cap for application to tumblers and the like, comprising a cover portion constructed to 55 form a closure for the mouth of a suitable vessel, and an annular skirt portion depending from the cover portion in position to encompass the side wall of the vessel; the said skirt portion being of resilient material preformed to provide an inwardly struck rib extending in the circumferential direction of the skirt and having the cross-sectional contour of intersecting conic surfaces so as to provide a narrow contact member disposed on a circumference smaller than that of the vessel wall portion upon which it is designed to seat so as to have frictional retaining engagement against the peripheral face of the vessel under the resilient tension of the material in the skirt; and portions of the skirt not included in said rib forming constraining members effective 60 upon the material in the rib to resist expansive movement thereof under pressure applied to the crest of the rib, whereby the cap is adapted for effective application to and removal from a suitable container repeatedly. 65
